UNITED STATES PATENT OFFICE

95,043

DESIGN FOR A PARCEL SHELF

Frederick W. Kent, Minneapolis, Minn.

Application September 17, 1934, Serial No. 53,310

Term of patent 14 years

To all whom it may concern:

Be it known that I, Frederick W. Kent, a citizen of the United States, residing at Minneapolis, in the county of Hennepin and State of Minnesota, have invented a new, original, and ornamental Design for a Parcel Shelf, of which the following is a specification, reference being had to the accompanying drawing, forming part thereof, wherein:—

Fig. 1 is a perspective view of a parcel shelf in closed position showing by new design, and

Fig. 2 is a perspective view of a parcel shelf in open or operative position, showing my new design.

What I claim is:—

The ornamental design for a parcel shelf, as shown and described.

FREDERICK W. KENT.
